UNITED STATES PATENT OFFICE.

JOSEPH HOPKINSON, OF DAYTON, OHIO.

COMPUTING-SCALE.

1,077,935.

Specification of Letters Patent.

Patented Nov. 4, 1913.

Application filed May 1, 1911. Serial No. 624,351.

To all whom it may concern:

Be it known that I, JOSEPH HOPKINSON, a citizen of the United States, residing at Dayton, in the county of Montgomery and State of Ohio, have invented certain new and useful Improvements in Computing-Scales; and I do hereby declare the following to be a full, clear, and exact description of the same, reference being had to the accompanying drawings, forming a part of this specification, and to the figures and letters of reference marked thereon.

In the practical development of computing scales, particularly the type embodying a rotating drum having its surface covered with figures indicating values of goods weighed on the scale, the necessity has arisen of providing a means whereby the value and price indications may be properly illuminated so as to be readily seen and read by the salesman as well as the purchaser. Various expedients have been tried for accomplishing this result, and among the later developments along this line have been a means whereby the drum might be artificially illuminated, and being made of translucent material, the figures appearing at the sight opening would be made very plain, so as to be readily seen and read. Such scales as thus far developed have embodied means whereby an electric light or lights might be employed, such lights being normally extinguished, but through switch or contact devices lighted when the scale is put in operation as when a load is placed on the load support. Patents numbered 886,775 and 946,447, illustrate the type of scale above referred to, and it will be understood that in the scale of the present invention similar means may be employed for establishing or breaking an electric circuit for lighting or extinguishing the lights or lamps used for illuminating the scale, and hence no particular description of this mechanism is thought to be necessary. In all of the scales heretofore constructed difficulty has been experienced in so illuminating them that the figures both on the rotary drum and on the fixed casing would be

brought into prominence, and although it has been proposed to form perforated figures or price characters on the fixed portion of the casing which would be illuminated from within or by light transmitted through the wall of the drum, the result has not been entirely satisfactory, nor has such

an arrangement presented possibilities of effective advertising by means of the illuminating light, nor of giving the scale a highly ornamental character which can be secured if illuminating devices external to the drum be employed.

In accordance with the present invention, it is proposed to primarily illuminate both the price indications on the fixed casing and the value indications on the rotary drum from the exterior or side from which they are viewed, although, as will be presently explained, a certain proportion of the light may be transmitted into the interior of the drum for illuminating the whole interior to a greater or less degree. In carrying the invention into practice, the casing embodies or has thereon an offset portion extending parallel with the sight opening, said offset portion constituting a light chamber in which an illuminating device is located, and said chamber has an elongated opening through which the light passes to illuminate the front or outer side of the price and value indications, and by reason of the fact that the light is located in such a chamber exterior to and parallel with the drum, it becomes possible to utilize the light as an effective advertising medium as well as to enhance the attractiveness and beauty of the scale. For instance, by making the chamber in whole or in part, of translucent material, such as colored glass, having advertising matter thereon, or of the so-called "art-glass."

Referring to the accompanying drawings: Figure 1 is an end elevation partly in section of a scale embodying the present improvements; Fig. 2 is a front elevation of the scale shown in Fig. 1; Fig. 3 is an elevation partly in section showing a modified arrangement of the illuminating portion of the scale.

Like letters of reference throughout the several figures indicate the same parts.

Referring to Figs. 1 and 2, the scale illustrated embodies the well known elements of a rotary drum A, counterbalancing springs B, and draft bar or load support C, the drum and counterbalancing springs being mainly shown in dotted lines. The drum is of ordinary construction, that is to say, its periphery is covered with translucent material, such as varnished paper, upon which is printed in proper order the value indications. The drum and counterbalancing

springs are inclosed by a case D which is preferably generally cylindrical in form, and may be mounted upon the upper ends of the standards d which extend down to 5 and are carried by a base, not shown.

Formed in the front of the casing and parallel with the axis of the rotary drum is a side opening E through which the value computations on the drum are exposed from 10 one end to the other, this sight opening being preferably formed in a plate which, while separable from the body of the casing, forms in the assembled scale a portion of the casing in that it incloses the front of 15 the drum and defines the size and position of the sight opening.

In accordance with the present invention the casing is formed or provided with an offset or chamber parallel with the sight 20 opening and located, as shown in Figs. 1 and 2, in front of and above said opening, said chamber, however, being so related to the sight openings that when itself strongly illuminated, the light will pass down in front 25 of and into the sight opening, thereby illuminating both of the sets of figures before referred to; *i. e.*, the set of price figures on the outer face or wall of the portion of the casing forming the sight opening and 30 the figures on the periphery of the drum at the sight opening. In the preferred arrangement the upper portion or top of the offset indicated at F extends in a more or less tangential direction from the upper 35 portion of the casing or top of the drum, and at its end is provided with an upright wall G which may be in the form of a colored glass panel adapted to display advertising or interest exciting matter, the lower 40 portion of said front wall being preferably extended down past the sight opening and joining the body of the casing below the same, as at H. Conveniently, opposite the sight opening the offset carries a magnifying 45 lens I, although it will be understood that a plain glass lens may be substituted or used where magnification of the indications is not desired, and furthermore, that while the illuminating chamber is thus 50 opened downwardly to the sight opening, a portion of the light may, if so desired, be transmitted to the sight opening through the lens itself, as illustrated, for instance, in Fig. 3, which will be hereinafter referred to.

The lamp or light is preferably a long incandescent electric lamp located in the upper portion of the illuminating chamber, and, if desired, in a curved hood or recess f, the 60 position being such that the rays of light will effectually illuminate the ornamental panel G, as well as the lines of price and value indications at the sight opening. Where so desired, the inner wall of the offset or illuminating chamber above the por-

tion of the casing forming the sight opening is entirely or partly removed, thus exposing the periphery of the drum directly to the light from the chamber, which light, being transmitted through the periphery of 70 the drum, will illuminate its whole interior, thus rendering parts visible which might otherwise be obscured by shadow, and aiding materially in causing the figures at the sight opening to stand out clearly. On the reverse or rear side of the scale, a similar arrangement of illuminating chamber may be employed, as shown clearly in Fig. 1, only in this instance it becomes unnecessary 75 to provide a long downward extension of the chamber, in view of the fact that no elongated sight opening is employed, but only a sight opening indicating pounds and ounces, usually at substantially the center line of the scale. Sufficient light for illuminating this sight opening will be transmitted through the wall of the drum from the electric light K, located above the sight opening. On the rear side of the scale the panel G' is 80 for the purpose of displaying attractive advertising or interest exciting matter, and the lower wall of the chamber at H' connects directly with the cylindrical wall of the casing. The electric lamps K and K' will both be of substantially the same character, and while both are preferably employed, it is obvious that one will give good results, although it should not be of such character as would endanger the parts of 85 the scale from overheating.

In Fig. 3 the illuminating chamber is formed by an overhanging hood or projection M in which the electric light N is located at a point sufficiently high to prevent its direct rays shining out into the eyes of the person using the scale, while below said hood the projection or offset portion O carrying the lens P is open at the top as indicated at p. The front wall of the projection O, however, is not removed sufficiently far from the drum to cause all of the rays of light to pass within the same and consequently some of the light will reach the sight opening through the lens while a part of the light will pass down behind the lens for direct illumination of the sight opening and indicating characters exposed thereat.

It will be understood, of course, that the inner surface of the walls of the illuminating chamber which are not intended to transmit light may be in the form of reflecting surfaces, thereby concentrating the light on those portions of the scale which it is desired to illuminate.

Having thus described the invention, what I claim as new and desire to secure by Letters Patent of the United States, is:

1. In an illuminated computing scale, the combination with a rotary cylindrical drum 130

having value computations on its peripheral surface, load supporting counterbalancing mechanism for rotating the drum, and a cylindrical casing inclosing the drum and having 5 a sight opening extending parallel with the axis of the drum with price computations on the exterior face in proximity to the sight opening, of an elongated light chamber extending parallel with and above the sight opening, said chamber forming an offset on the outer side of the casing and being open at the bottom in front of the sight opening in the casing, whereby the computations on the exterior face of the casing in proximity to the sight opening and the value computations on the exterior face of the drum at the sight opening are illuminated from the front of the scale, and a source of light located within the light 15 chamber and above a portion of said chamber lying in front of the same, whereby the eyes of the observer are shielded from the direct rays of the light.

2. In an illuminated scale, the combination with the rotary cylindrical drum having value computations on its exterior peripheral face, and load supporting and counterbalancing mechanism for rotating the drum, of an inclosing casing for the drum having a sight opening extending parallel with the axis of the drum, an external light chamber mounted on and forming a part of the casing, and extending parallel with and in proximity to the sight opening, a lens extending parallel with and in front of the sight opening, there being openings for the transmission of light both toward the front and the rear sides of the lens, and a source of light located in said chamber in position to transmit its luminous rays through said openings toward the front of the lens and also back of the lens to illuminate the front faces of the casing having the price com-

putations thereon and of the drum having the value computations thereon.

3. In an illuminated computing scale, the combination with the rotary drum having value computations thereon, load supporting and counterbalancing mechanisms for rotating the drum, and a casing surrounding the drum and having a sight opening extending parallel with the axis of the drum with price computations in proximity thereto, of a casing extension forming a chamber in front of and above said sight opening, the wall of said extension being formed in part by a lens in front of the sight opening and translucent material above the lens and a source of light located above and in front of the sight opening in the chamber, formed by the casing extension whereby the light will illuminate both the price and value computations from the front and be in part transmitted through the translucent material.

4. In an illuminated computing scale, the combination with the rotary drum having value computations thereon and load supporting and counterbalancing mechanism for rotating the drum, of a casing surrounding the drum and having an offset extending parallel with the axis of the drum to form a light chamber, a portion of the wall of said chamber being of light transmitting substance, and a portion having a sight opening therein parallel with and in proximity to the drum, and a source of light located in the chamber for illuminating the sight opening and computations exposed thereat and for being displayed through the light transmitting wall of the chamber.
